PRESSURE ACTUATED TOOL

Rudolph H. Garbe, Forest Park, Ill., assignor to
 Western Electric Company, Incorporated, New
 York, N. Y., a corporation of New York

Application October 9, 1942, Serial No. 461,493

11 Claims. (Cl. 10—128)

This invention relates to pressure actuated tools and more particularly to a punch press actuated thread tapping apparatus.

It is an object of the present invention to provide a simple and inexpensive apparatus for operating rotary tools.

In accordance with one embodiment of the invention, tapping tools are driven by the ram of a punch press to tap holes in an article while other tools in the press are performing other operations. A large piston driven by the press applies pressure to drive a smaller piston for actuating a tap driving member through a greater distance than the stroke of the ram.

A better understanding of the invention may be had by reference to the detailed description when considered in conjunction with the accompanying drawing, wherein the single figure shows, in section, the ram of a punch press and the mechanisms driven thereby for driving tapping tools and comprises an illustration of one embodiment of the present invention.

In the drawing, the ram of a punch press 1 has formed integrally with it a punch supporting plate 2, in which punches 3 and 4 may be suitably fixed for cooperation with a die block 5 mounted upon an interposer plate 6, which, in turn, rests upon a bed 7 of the punch press. The punch supporting plate 2 carries other tools in addition to the punches 3 and 4, which are not of interest in connection with the present invention and which are, therefore, not shown, but it will be understood that the punch press is of the type using the usual progressive tools whereby a series of operations may be performed on a strip of material in any suitable manner and that the material 8 may be fed through the apparatus by any suitable means (not shown). It will be further understood that the punches 3 and 4 are simply illustrative of any of a number of different types of tools which might be used, but, in the present case, have been shown as operative to punch holes 9 and 10 in the strip of material 8, the side walls of which holes are to be threaded by taps 11 and 12, respectively.

In the preferred embodiment of the invention, a stripper plate 13 is attached to the punch supporting plate 2 by means of pins 14 and 15 threaded into the stripper plate 13 and having heads 16 and 17 nesting in shouldered apertures 18 and 19 in the punch supporting plate 2. Surrounding the pins 14 and 15 are coil springs 20 and 21, which are interposed between the undersurface of the punch supporting plate 2 and the upper surface of the stripper plate 13, thereby normally

to urge the plate 13 downwardly against the strip of material 8.

Threaded into the punch supporting plate 2, and adjustably located in position therein by a lock nut 22, is a piston actuating rod 23, which extends through the bed 7 of the press and abuts at its lower end a piston 24. The piston 24 is movable within a cylinder 26, in which there is contained a supply of oil or other suitable fluid 10 which will be forced through a port 27 in the cylinder into a pipe 28 when the piston actuating rod 23 is moved downwardly by the punch supporting plate 2 of the punch press. The fluid forced downwardly through the pipe 28 will be 15 carried through suitable piping 29 and through a port 30 into a cylinder 31, which is of an appreciably smaller diameter than the cylinder 26 and which is correspondingly appreciably deeper than the cylinder 26, whereby when the fluid under pressure is displaced from the cylinder 26 by the downward movement of the piston 24, a piston 32 in the cylinder 31 will be driven upwardly a much greater distance than the piston 24 is driven downwardly.

25 The cylinder 26 is connected directly to the underside of the bed 7 of the punch press, whereas the cylinder 31 is mounted upon a plate 33 positioned beneath the bed 7 and attached to the bed by means of support rods 34 and 35. The 30 support rods 34 and 35 are reduced at their ends and are threaded into the bed 7 of the press and also have shoulders 36 and 37 against which the plate 33 is held by nuts 38 and 39 threaded onto the reduced ends of the rods 34 and 35. Thus, 35 the plate 33 is rigidly secured in position beneath the bed 7 of the press.

The piston 32 has fixed to it a piston rod 45 having a slidable plate 46 attached to its upper end for reciprocation with the piston rod 45 under 40 the influence of the piston 32. The plate 46 is normally urged downwardly by compression springs 47 and 48 surrounding rods 49 and 50, which are threaded into the plate 46 and are provided with retaining nuts 51 and 52 at their lower 45 ends between which retaining nuts and the underside of the plate 33 the springs 47 and 48 are compressed. Thus, the springs 47 and 48 will tend to drive the rods 49 and 50 downwardly to draw the plate 46 downwardly with them.

50 Set into the plate 46 are a pair of threaded bushings 53 and 54, which may be secured in the plate 46 in any suitable manner and which engage the threads of a pair of spindles 55 and 56 to impart rotary motion to the spindles 55 and 55 56 as the plate 46 is reciprocated vertically. The

spindles 55 and 56 bear in thrust bearings 57 and 58 formed in the plate 33 and in bearings 59 and 60 formed in a bearing plate 62, which is held on the underside of the bed 7 of the press by shoulders 61 and 62 at the end of the reduced portions of the supporting rods 34 and 35. The spindles 55 and 56 extend upwardly through the bed 7 of the press and are provided at their upper end with sockets 65 and 66, respectively, which are rectangular in cross section and are adapted to receive the shanks 67 and 68 of tap holders 69 and 70, respectively, in which the taps 12 and 11 are fixed by means of set screws 71 and 72, the lower ends of the taps being cut away, as shown, for example, at 73, to lock against rotation in the tap holders 69 and 70.

Set into the die block 5 is a guide plate 74, which serves to guide the taps 11 and 12 into the holes 9 and 10 punched in the strip of material 8, so that as the taps 11 and 12 are advanced toward the strip of material 8, there will be no tendency for them to improperly engage with the holes 9 and 10. The stripper plate 13 is also provided with apertures 75 and 76 coaxial with the taps 11 and 12, respectively, so that the taps may freely pass through the stripper plate 13. The tap holders 69 and 70 have external threads formed thereon of the same pitch as the threads on the taps 12 and 11, respectively, for engaging internal threads formed in apertures 77 and 78 formed in the die block 5 so that as the taps rotate with the spindles 55 and 56, the rate of advance of the taps will be controlled by the cooperating threads on the tap holders 69 and 70 and in the apertures 77 and 78, respectively, whereby, although the spindles do not reciprocate, the taps will advance with the tap holders 69 and 70 and carry the square shanks 67 and 68 of the tap holders 69 and 70 upwardly at the same rate that the thread is to be cut in the holes 9 and 10.

In the operation of the apparatus, two holes 9 and 10 will be tapped simultaneously for each stroke of the punch press ram 1 and the travel of the plate 46 will be greater than the travel of the ram 1, whereby the desired amount of rotation may be imparted to the spindles 55 and 56, although the stroke of the punch press is relatively small due to the fact that the large amount of fluid displaced by the piston 24 in its short travel downwardly will impart a relatively great amount of travel to the smaller piston 32. If it is desired to change the amount of rotation of the taps 11 and 12, the position of the rod 23 may be adjusted with respect to the plate 2 so that the rod 23 will strike and actuate the piston 24 either earlier or later in the stroke of the ram 1 and impart more or less travel to the piston.

What is claimed is:

1. A press-operated article-forming apparatus comprising a rotatable tool, a spindle for imparting rotation to said tool, means reciprocable with respect to the spindle for rotating it, a piston for driving said reciprocable means, a second piston larger in diameter than the first mentioned piston, connecting means for confining a supply of fluid between said pistons, and a press driven ram for actuating the second piston.

2. The combination of a positively driven ram with a rotary tool to be driven thereby comprising a piston of relatively large diameter driven by said ram, a second piston of relatively small size with respect to the first mentioned piston and having a longer stroke than the first-mentioned piston, connecting means for confining a

supply of fluid between the first-mentioned piston and the second-mentioned piston whereby movement imparted to one piston will be transmitted to the other piston, means driven by said second piston, a spindle rotatable by said means and driven by the second piston, and means interconnecting said spindle and the rotary tool.

3. In a punch press actuated apparatus, a rotary tool, a press actuated ram, a piston driven by said ram, a second piston, connecting means for confining a supply of fluid between the first-mentioned piston and the second-mentioned piston whereby movement will be imparted to one piston when the other piston is moved, and means actuated by the second piston for rotating the tool.

4. In a punch press actuated apparatus, a rotary tool, a press actuated ram, a piston driven by said ram, a second piston having a smaller diameter and longer stroke than the first mentioned piston, connecting means for confining a supply of fluid between the pistons whereby motion imparted to one piston will be transmitted to the other piston and means actuated by the second piston for rotating the tool.

5. In a punch press actuated apparatus, a rotary tool, a press actuated ram, a piston driven by said ram, a second piston, connecting means for confining a supply of fluid between said pistons, a threaded plate carried by said second piston, and a spindle threadedly engaging the threads in the plate for rotation thereby and carrying said rotary tool.

6. In a punch press actuated apparatus, a rotary tool, a press actuated ram, a piston driven by said ram, a second piston, connecting means for confining a supply of fluid between said pistons, a plate carried by said second piston for reciprocation thereby, means for urging said plate in a predetermined direction, a spindle threaded in said plate for rotation by said plate upon reciprocation of the plate, means for holding the spindle against longitudinal movement, and a tool carrier rotatable with and slidably longitudinally of the spindle for driving the rotary tool.

7. In a punch press actuated apparatus, a rotary tool, a press actuated ram, a piston driven by said ram, a second piston, connecting means for confining a supply of fluid between said pistons, a plate carried by said second piston for reciprocation thereby, means for urging said plate in a predetermined direction, a spindle threaded in said plate for rotation by said plate upon reciprocation of the plate, means for holding the spindle against longitudinal movement, a tool carrier rotatable with and slidably longitudinally of the spindle for driving the rotary tool, and a fixed plate threadedly engaging the tool carrier to determine its rate of longitudinal movement.

8. In a punch press actuated apparatus, a rotary tool, a press actuated ram, a piston driven by said ram, a second piston, connecting means for confining a supply of fluid between said pistons, a plate carried by said second piston for reciprocation thereby, a spindle threaded in said plate for rotation by said plate upon reciprocation of the plate, bearings for holding the spindle against longitudinal movement and permitting rotation thereof, and a tool carrier rotatable with and slidably longitudinally of the spindle for driving the rotary tool.

9. In a punch press actuated apparatus, a rotary tool, a press actuated ram, a piston driven by said ram, a second piston, connecting means for confining a supply of fluid between said pis-

tons, a plate carried by said second piston for reciprocation thereby, means for urging said plate in a predetermined direction, a spindle threaded in said plate for rotation by said plate upon reciprocation of the plate, means for holding the spindle against longitudinal movement, a tool carrier rotatable with and slidable longitudinally of the spindle for driving the rotary tool, and means for determining the rate of advance of the tool.

10. A punch press actuated apparatus comprising a reciprocating ram having a predetermined length of stroke, a rotary tool, and means interconnecting the ram and tool for rotating the tool including a reciprocal member for rotating

the tool and means actuated by the ram for reciprocating the reciprocal member a greater distance than the stroke of the ram.

5 11. A punch press actuated apparatus comprising a reciprocating ram, means actuated by said ram for punching an aperture in an article, a tapping tool for threading said aperture, and means for imparting a greater movement to said tapping tool than the movement of the ram including a reciprocating member and means interconnecting the ram and said member to impart a greater movement to said member than the movement of the ram.
